UNITED STATES PATENT OFFICE.

LEO GRUBMAN, OF NEW YORK, N. Y., ASSIGNOR TO ELECTRIC SPARK APPLIANCE CO. INC., OF NEW YORK, N. Y., A CORPORATION OF NEW YORK.

ELECTROMAGNETIC RESONATOR.

1,181,446.

Specification of Letters Patent.

Patented May 2, 1916.

Application filed March 16, 1914. Serial No. 825,114.

To all whom it may concern:

Be it known that I, LEO GRUBMAN, a citizen of the United States, and a resident of the borough of Brooklyn, county of Kings, 5 city and State of New York, have invented certain new and useful Improvements in Electromagnetic Resonators, of which the following is a specification.

My improvements relate to the class of 20 resonators in which a diaphragm is vibrated by means actuated by electro-magnetism, as for instance in connection with horns for directing sound warnings, or for analogous purposes, the object being to render the device 25 simple and compact in its construction and arrangement of parts, and to eliminate all but the essential elements, at the same time rendering the device durable and effective.

29 The invention consists in the novel features described and claimed specifically, a distinctive feature being the utilization of the electro-magnet itself, particularly one member thereof, as a base or foundation 35 plate upon which all the other parts are mounted and supported, this basic member being dish-shaped, and accommodating between it and the other member of the electro-magnet the electric coil, and also the 40 condenser when used in conjunction therewith, as hereinafter more fully set forth.

In the accompanying drawings, Figure 1, 35 is a rear sectional elevation of my improved resonator, the section being taken through the casing only, and the circuits, &c., being shown diagrammatically and symbolically; Fig. 2, is a central vertical sectional elevation of the device; Fig. 3, is an isometrical section of the dish-shaped member of the 40 electro-magnet.

In my concurrent application No. 710,676, filed July 20th, 1912, I show a somewhat similar construction of electro-magnet, but in that application I confine myself more 45 particularly to the anti-sparking means, method of winding, &c., whereas in the present case I seek to cover more particularly the mechanical construction and arrangement of parts. Of these the more important 50 is the magnetic member B, which to all intents and purposes practically constitutes the base or foundation plate upon which the rest of the structure is built up and supported. In cross section this basic member 55 is essentially dish-shaped, and it is prefer-

ably annular or cylindrical in external configuration. Thus it may consist of a shallow cylindrical portion or annular wall b, having the outer peripheral flange b', and the inner disk flange b'', the latter formed 60 with the central aperture b'''—said inner annular disk flange b'', constituting the bottom, and the peripheral flange the annular lip, of the dish-shaped magnetic member B, the extreme inner edge b''', of which forms one pole 65 of the electro-magnet in action. The other pole is afforded by the central portion d', of the magnetic disk member D, of the electro-magnet, which member D, is rigidly bound to the base member B, by screw bolts 70 s, s', the two members B, D, of the magnet being positioned apart by intermediate magnetic spacing blocks or washers q, q'. The central portion d'', of the disk member D, is preferably made in the form of a cylindrical boss projecting toward the central 75 aperture b''', of the member B, so that the poles b''', d'', are in operative proximity to each other and to the armature A, the face a, of which latter protrudes into the central 80 aperture b''', of the dish-shaped member B, as shown in Fig. 2.

The peripheral edge d', of the disk member D, contacts with the inner surface of the cylindrical wall b, of the dish-shaped member B, so as to connect magnetically therewith to form one limb of the electric magnet. The two said members B, D, are also connected magnetically by the spacing 85 blocks q, q'. 90

The cylindrical boss d', is formed with a central guide opening in which is seated the reciprocating plunger p, interposed loosely between the face a, of the armature A, and the resilient diaphragm R. The usual pulsations of the armature A, under the influence of the intermittent attraction of the magnet B, D, are transmitted to the diaphragm R, by the plunger p,—the retractile movement of the armature being effected by the resilience 95 of the spring a', upon which it is mounted, said spring being clamped between spacing blocks a'', a''', held in place against the rear side of the dish-shaped member B, by the screw bolts s', s'. While I prefer the 100 loosely mounted plunger p, herein shown and described I do not necessarily limit myself thereto, since any intermediate means for transmitting the vibratory movements of the armature A, to the resilient diaphragm 105 110

R, may be substituted with substantially like result in so far as the other features of my structure are concerned. These screw bolts s , s' , also secure in position the bracket e , 5 on which the adjustable interruption or "make and break" contact i , is mounted, said bracket and its supporting block e' , being insulated from the bolts s , s' , and also carrying the binding screws e^2 , e^3 , by which connection is made with the circuit wires w , w' , 10 from the battery W .

The elastic resilient plate γ , which in conjunction with the contact i , acts as the current interrupting means, is secured by the 15 bolts s , s' , and spacing blocks γ^2 , γ^3 , to the rear side of the basic member B, being insulated from said bolts by the usual method. This make and break spring plate γ , bears against a rest α^4 , of insulating material on 20 the armature A, and tends constantly to press the latter toward the poles of the electro-magnet B, D, which tendency is counteracted normally by the spring α' , upon which the armature is mounted.—The armature spring α' , in turn tending constantly 25 through the medium of the rest, α^4 , to maintain the interruption plate γ , in electrical engagement with the contact i , on the bracket e , thereby closing the electric circuit. 30 Thus closed, the current energizes the magnet B, D, which deflects the armature A, causing the latter to strike the plunger p , and transmit the movement to the resilient diaphragm R.

35 The deflection of the armature A, allows the interrupting spring γ , to break away from the contact screw i , and open the circuit, it being understood that said elements i , γ , are included in the normal circuit. The 40 opening of the circuit, thus effected, of course cuts off the current from the coil C, the members B, D, are thereby demagnetized, and the armature A, is retracted by its spring support α' , carrying the plate γ , back 45 into electrical engagement with the contact i , and again closing the circuit, when the cycle is repeated so long as the battery circuit is maintained closed by means of the push button or equivalent device f . This is essentially 50 the operative method of most devices of this class, a feature of novelty in the present connection being the inclosure of the coil C, within the dish-shaped member B, of the magnet, and between said member and the 55 disk-shaped member D, of said electro-magnet, as shown symbolically in Fig. 2, of the drawings. Where a condenser C', is used in conjunction with the coil C, interposed in the usual manner in the spark gap, said condenser may be arranged at the side of the 60 coil C or otherwise related thereto. Said condenser is also included between the magnetic members B, D, and like the coil C, connected up in a manner well known in the 65 art,—my present invention as before inti-

mated not relating especially to the electric system, but rather the mechanical arrangement of parts.

The coil C, is positioned adjacent the central opening b^3 , in the base member B, and around the cylindrical boss d^4 , on the other member D, of the electro-magnet, as is also the condenser C', when used, and for the centralization and support of the coil, or coil and condenser, as the case may be, an annular block m , of insulating material may be placed upon the pole boss d^4 , as shown in Fig. 2.

The rear casing K, is secured by preference directly to the cylindrical wall b , of the 80 dish-shaped member B; and in like manner the front cap L, may be attached to the peripheral flange b' , of the dish-shaped member B, a spacing pad or washer l , being interposed between. The horn H, may be 85 mounted on the cap L, which latter affords the usual resonance chamber l^2 , in front of the diaphragm R.

From the foregoing it will be readily seen that my device is unique in structure in that 90 the magnet itself affords isolation and support for the coil and condenser, while performing the function of a base on which all other parts of the device are mounted either directly or indirectly. Other advantages 95 are, economy of construction; and efficiency of magnetic field, since all parts of the coil are in proximity to the magnetic current. Furthermore the armature and the pull 100 thereon, being central, even and uniform action on the transmitting plunger is attained as compared with the use of the old form of two-coil electro-magnet and armature acting on a pin or stud attached directly to the diaphragm.

105 What I claim as my invention and desire to secure by Letters Patent is,

1. In an electro-magnetic resonator of the character designated, a two-part electro-magnet consisting of a dish-shaped member 110 formed with a central opening and a disk member fitted within the dish-shaped member and having a central projection opposite said opening, said members being arranged in close proximity to each other, an 115 electric exciting coil positioned between them and inclosed by one of said members, a resilient diaphragm supported on the outer peripheral flange of the dish-shaped member, a retractile armature supported at the 120 rear side of said dish-shaped member and having a portion extending into said opening, and a plunger loosely seated in the disk member and interposed between said diaphragm and armature for direct engagement with both.

2. In an electro-magnetic resonator of the character designated, a two-part electro-magnet consisting of a dish-shaped member 125 formed with a central opening and a disk 130

member fitted within the dish-shaped member and having a central pole boss coincident with said opening, an electric exciting coil disposed between said members, a resilient diaphragm supported on the peripheral flange of the dish-shaped member, a retractile armature supported at the rear side of the dish-shaped member and formed with a part disposed opposite said opening, and 10 loosely mounted means directly engageable with said armature and diaphragm.

3. In an electro-magnetic resonator of the character designated, a two-part electro-magnet consisting of a dish-shaped member formed with a central opening and a disk member fitted within the dish-shaped member and having a central pole boss coincident with said opening, an electric exciting coil disposed between said members, 15 a resilient diaphragm supported on the peripheral flange of the dish-shaped member, a retractile armature supported at the rear side of the dish-shaped member and formed with a part disposed opposite said opening, loosely mounted means directly engageable with said armature and diaphragm, and a current interrupter to the rear of said armature.

4. In an electro-magnetic resonator of the character designated, in combination, a two part electro-magnet consisting of a dish-shaped member formed with a central opening and a disk member fitting said dish-shaped member and formed with a central pole boss coincident with the central aperture in the latter, an electric exciting coil positioned between them, a resilient diaphragm supported on the peripheral flange of said dish-shaped member, a retractile armature supported upon the rear side of said dish-shaped member and formed with a part protruding into the central opening in said dish-shaped member, and means interposed between the resilient diaphragm and the said retractile armature for transmitting the motion of said armature to said diaphragm, for the purpose described.

5. In an electro-magnetic resonator of the character designated, in combination, a two part electro-magnet consisting of a dish-shaped member formed with a central opening and a disk member fitting said dish-shaped member and formed with a central pole boss coincident with the central aperture in the latter, an electric exciting coil positioned between them, a resilient diaphragm supported on the peripheral flange of said dish-shaped member, a retractile armature supported upon the rear side of said dish-shaped member and formed with a part protruding into the central opening in said dish-shaped member, a plunger loosely seated in the central boss on said disk member and interposed between the resilient diaphragm and the said retractile

armature, and current interrupting means also supported on the rear side of said dish-shaped member, for the purpose described.

6. In an electro-magnetic resonator of the character designated, in combination, a two part electro-magnet consisting of a dish-shaped member formed with a central opening and a disk member fitting said dish-shaped member and formed with a central pole boss coincident with the central aperture in the latter, an electric exciting coil and a condenser positioned between them, a resilient diaphragm supported on the peripheral flange of said dish-shaped member, a retractile armature supported upon the rear side of said dish-shaped member and formed with a part protruding into the central opening in said dish-shaped member, a plunger loosely seated in the central boss on said disk member and interposed between the resilient diaphragm and the retractile armature, and current interrupting means also supported on the rear side of said dish-shaped member, for the purpose described.

7. In an electro-magnetic resonator of the character designated, an armature, a diaphragm, a two-part electro-magnet consisting of a dish-shaped member forming the base and having an opening therein, and a disk member disposed within said dish-shaped member and having a portion extended toward said opening, and forming with the walls of said opening the poles of the magnet and means independent of said armature and diaphragm and movable axially through the disk member for direct contact with said armature and diaphragm.

8. In an electro-magnetic resonator of the character designated, an armature, a diaphragm, a two-part electro-magnet consisting of a dish-shaped member forming the base and having an opening therein, and a disk member disposed within said dish-shaped member and having a portion extended toward said opening and forming with the walls of said opening the poles of the magnet, said members being arranged in proximity to each other and a coil surrounding said portion and means independent of said armature and diaphragm and movable axially through the disk member for direct contact with said armature and diaphragm.

9. In an electro-magnetic resonator of the character designated, a two-part electro-magnet consisting of a dish-shaped member forming the base and having an opening therein, a disk member disposed within said dish-shaped member and having a portion extended toward said opening and forming with the walls of said opening the poles of the magnet, said members being arranged in proximity to each other, a coil surrounding said portion, and an armature movable in said opening.

10. In an electro-magnetic resonator of the character designated, a two-part electro-magnet consisting of a dish-shaped member forming the base and having an opening 5 therein, a disk member disposed within said dish-shaped member and having a portion extended toward said opening and forming with the walls of said opening the poles of said magnet, said members being 10 arranged in proximity to each other, a coil surrounding said portion, an armature movable in said opening, and a plunger movable in said portion and extended at one end to be engaged by said armature.
15. 11. In an electro-magnetic resonator of the character designated, an armature, a diaphragm, a two-part electro-magnet consisting of a dish-shaped member forming the base and having an opening therein, and 20 a disk member disposed within said dish-shaped member and having a portion extended toward said opening, and forming with the walls of said opening the poles of the magnet, said members being disposed in 25 proximity to each other, means independent of the armature and diaphragm movable axially through the disk member for direct contact with said armature and diaphragm, a coil within the dish-shaped member and 30 surrounding said portion, and coöperating means arranged in the rear of said dish-shaped member.
12. In an electro-magnetic resonator of the character designated, a two-part electro- 35 magnet consisting of a dish-shaped member and a disk member fitted therein, the dish-shaped member having an opening therein,

the inner face of said member forming one pole of an electro-magnet, an armature, a diaphragm, a member disconnected from 40 said armature and diaphragm and loosely movable through said disk member for direct contact with both the armature and diaphragm and an exciting electric coil interposed between the disk member and the 45 body portion of the dish-shaped member.

13. In an electro-magnetic resonator of the character designated, a dish-shaped member constituting a magnet and having a flange for direct support of a diaphragm, 50 means for securing a diaphragm to said flange, a disk member within the dish-shaped member, and a coil between the said two members, a diaphragm, and means independent of the diaphragm and loosely 55 movable through said disk member for direct contact with the diaphragm.

14. In an electro-magnetic resonator of the character designated, a dish-shaped member constituting a magnet and having a flange for direct support of a diaphragm, a diaphragm means for securing said diaphragm to said flange, a disk member within the dish-shaped member, a coil between the said two members, an armature, and means loosely movable through said disk member and independent of the armature and diaphragm and actuated by said armature to transmit movement to said diaphragm.
